UNITED STATES PATENT OFFICE

ROBERT W. McDANIEL, OF MEMPHIS, TENNESSEE

HOT-WATER HEATER AND BURNER

Application filed August 22, 1929. Serial No. 387,650.

This invention relates to new and useful improvements in hot water heaters or furnaces and burners therefor; and has for its objects to provide an efficient burner and heater which will heat up quickly, which will conserve the heat of the fuel and utilize all thereof and which may therefore be economically fuelled once each day, and which can be easily and economically constructed. A further object is to provide such a device having storage both for heat and water.

These objects are accomplished by providing a plurality of annular water legs depending from a common dome or head, the outer of such legs extending downward and surrounding the fire chamber; and by providing in this chamber an efficient type of gas heater or burner so designed as to conserve the heat and deliver same to the water storage chambers after the heating flame is extinguished, as will readily be understood from the following specification on reference to the accompanying drawings, in which:

Fig. 1, is a vertical sectional elevation taken substantially on the center line;

Fig. 2, is a horizontal section taken as on the line II—II of Fig. 1;

Fig. 3, a similar section taken as on the line III—III; and

Fig. 4, also a similar section of the burner only, taken as on the line IV—IV of the same figure.

Referring now to the drawings the heater in its preferred form comprises three annular water legs 10, 11 and 12 which depend from the common water chamber 13. The outer water leg 10 extends downward to the bottom of the fire chamber 14 and forms the outer wall thereof, this leg rests on a base 15, preferably a cylindrical concrete pier extending upward from the floor level 16. Preferably also the outer water leg is entirely surrounded by an annular layer of insulating material 17, preferably asbestos, which may be retained if it be so desired by a metal shell 18. The two inner water legs extend only partially as far down as the outer leg, the inner leg being shortest, so that an annular combustion chamber is formed having a stepped crown from the center of which a flue

19 extends upward through the center of the water chamber 13 terminating slightly above the dome 20, which forms the top of such chamber. Disposed on this extension 21 is a T 22 having a horizontally extending portion 23 which leads to the usual wall or chimney flue. 24 is a damper and 25 a cap closing the upper end of the T 22. It will of course be understood that this flue may extend straight upward if preferred and the damper be located in such vertical flue. The horizontal flue 23 shown, may of course be turned in any direction desired so as to lead to a flue in any position.

Each water leg is formed by a pair of concentric annular shells joined at the bottom, and the adjacent shells of each pair of water legs as 10 and 11 are similarly joined at their upper end.

In order to avoid chance of dead air spaces between the upper ends of the water legs a tube 26 is extended through the water leg 12 adjacent the upper end thereof and a similar tube 27 through the water leg 11 in similar location, the two tubes preferably being axially aligned. A third tube 28 may be extended through the water leg 10 and the insulation 17 therearound in alignment with the tubes 26 and 27, these tubes providing a clean-out or inspection tube. 29 is a hinged door closing the outer end of the tube 28. 30 is an inlet pipe for cold water and 31 an outlet pipe for hot water. 32 is a drawoff pipe. 33 is a safety valve.

34 is an opening through the water leg 10 and the surrounding insulation 17 which is closed by a hinged door 35. This door serves as a coal door, should it be desired to heat the furnace with coal. 36 is a similar but preferably larger opening ordinarily disposed directly below the coal opening. This opening is closed by a door 37, and where coal is used, serves as an ash door.

I prefer however, to heat this furnace with gas. In such event, I prefer to use a burner of improved type, preferably circular in horizontal section and preferably having a base 42 which is a quadrant of a circular plate. From the radial edges of each of these quadrants vertical walls 43, 44 ex-

tend upward. Circular walls 39 which arch over at the top complete with the base of these walls gas chambers into which gas is delivered by the gas pipes 46, 47, 48 and 49. These pipes are controlled by individual valves 50, 51, 52 and 53 respectively. Intermediate the height of the walls 45 quadrant shaped plates 54 extend outward and from these plates radial extensions 55, 56 of the walls 42, 44 extend upward. Circular outer walls 57, and quadrant shaped top walls 58 complete the enclosure.

The completed units assembled, form a dome shaped gas chamber divided into segregated chambers by radial walls.

From the gas chambers formed by the enclosing walls 43, 44 and 45 a plurality of tubes 59 extend radially outward and project through the outer walls 57 forming burner nozzles. These tubes 59 are in successively higher banks which incline upward at progressively higher angles, the last bank 60 extending substantially vertically upward and projecting through the top plates 58. The space between these tubes is preferably filled with asbestos fiber 61. Each of the gas chambers is provided with an air inlet 62 which is regulated by an external slide 63, which may be in addition to usual air mixing devices on the pipes themselves.

The purpose of subdividing the burner into quadrants is threefold, first; in order that the amount of gas to be lighted at one time be reduced; second; in order that the various sections may be introduced through the ash door opening; and third, that one or more sections may be turned out after the water is hot. It will therefore be understood that the burner may be made in a single piece, if so desired, and also, that the number of subdivisions into individual units, or the number of subdivisions of an integral unit may be more or less than the number shown.

It will be further understood that the burner may be of any desired size or shape.

In using the heater it is filled with water in the usual manner through the pipe 30 from a suitable source of supply not shown. Gas may then be turned through one of the gas supply pipes into a section of the burner and this be lighted, after which additional sections may be lighted in succession. The heat of the combustion thus effected is directed by the individual gas pipes against the various water cells and as the amount of water in each is restricted in quantity, they will rapidly heat it up. At the same time, the asbestos packing around these burner tubes will also be heated so that a storage supply of heat will be set up in the burner itself, and such heat will be conserved in order that after the gas is turned off and combustion ceases the burner will radiate heat to maintain the water in heated condition.

It will of course be understood that the

heater may be used as a coal heater by simply removing the gas burner and building a coal fire in the furnace. Such fire may be replenished by putting coal in through the coal door and may be partially banked by placing ashes and cinders through the clean-out door.

It will further be understood that the usual types of the thermostat or other heat control devices may be used where gas is the fuel.

Having described my invention, what I claim is:

1. A gas burner for a hot water heater and heat conserving system, including a dome shaped shell, radial walls dividing said shell into a plurality of segregated gas chambers, said radial walls extending beyond said shell, an enclosing shell spaced from said first shell, a plurality of pipes forming burner nozzles extending from said chambers beyond said enclosing shell, a heat conserving medium disposed between said shells and surrounding said nozzles and means for supplying gas and air to said gas chambers.

2. A gas burner for a hot water heater and heat conserving system, including a segment of a dome shaped shell, radial walls forming with said shell a segmental gas chamber, said radial walls extending beyond said shell, an enclosing segmental shell spaced from said first shell, a plurality of tubes forming burner nozzles extending from said chamber beyond said enclosing shell, a heat conserving medium disposed between said shells and surrounding said tubes, and means for supplying gas and air to said gas chamber.

In testimony whereof I hereunto affix my signature.

ROBERT W. McDANIEL.
